Primary Examiner — Richard E Chilcot(57) **CLAIM**

The ornamental design for writing and drawing instrument, as shown and described.

DESCRIPTION

1. Writing and drawing instrument

1.1: Perspective

1.2: Left

1.3: Right

1.4: Top

1.5: Bottom

1.6 : Front

1.7 : Rear

1 Claim, 7 Drawing Sheets(56)
